FIG. 4

ATTY.

UNITED STATES PATENT OFFICE.

FRED E. PAYNE, OF MIDDLETOWN, CONNECTICUT, ASSIGNOR TO GOODYEAR RUBBER COMPANY, OF MIDDLETOWN, CONNECTICUT, A CORPORATION.

HEEL CONSTRUCTION FOR RUBBER FOOTWEAR.

1,161,879.

Specification of Letters Patent. Patented Nov. 30, 1915.

Application filed April 21, 1915. Serial No. 22,921.

To all whom it may concern:

Be it known that I, FRED E. PAYNE, a citizen of the United States, residing at Middletown, in the county of Middlesex and State of Connecticut, have invented certain new and useful Improvements in Heel Construction for Rubber Footwear, of which the following is a specification.

My invention relates to improvements in heel construction for rubber footwear, and the object of my improvement is simplicity and economy in construction and convenience and efficiency in use.

In the accompanying drawing:—Figure 1 is a side elevation of a rubber shoe embodying my invention. Fig. 2 is a bottom view, on an enlarged scale, of the heel portion of the same. Fig. 3 is a rear elevation of the same. Fig. 4 is a sectional view on the line *xx* of Fig. 2. Fig. 5 is a sectional view on the line *yy* of Fig. 2.

The shoe 10, shown in Fig. 1 is what is known as a men's overshoe rolled edge or coasting sole, comprising a sole portion having a rolled edge 11 and is provided with a special form of heel construction, embodying my invention, to be described. The said heel, as shown comprises a rolled heel edge 12 at the edge of the counter 13 or the heel portion of the body portion of the shoe 10, and an additional lift or tap 14 of special form on the lower face of the heel. The rolled heel edge 12, as is common in the ordinary construction without the additional lift 14 that I have provided, extends around the lower edge of the counter 13, and is in the form of a continuation of the bottom wall 15 of the heel end of the body portion extending slightly beyond the outer or side wall and curled over upwardly and inwardly, to meet the said side walls, being of appreciable depth and thickness. The lift 14 constitutes an addition to the construction described, and as mentioned is of special construction, and constitutes the tread portion of the heel. That is to say, the so-called bottom wall 15 serves as the closing wall for the counter 13, to provide a closed structure for the heel and the lift 14 serves as the tread, and is the part that wears away in use, and therefore the bottom counter wall or counter base 15 is relieved of the duty of withstanding the wear due to normal use, as in walking. Accordingly, the said counter base 15 may be made of rela-

tively thin material, and, furthermore, the lift 15 may be made of skeleton construction, as shown. Furthermore, as such skeleton construction exposes a portion of the counter base 15, I provide a panel 16 on the exposed portion 17, which it will be noted is protected by the said lift 14.

The particular form of the lift 14 as shown comprises a generally U-shaped structure, of appreciable thickness, extending around the sides and rear of the counter base 15, having a space 18 between the arms and opening into the arch portion 19.

The panel 16 is located within the space 18, inclosed by the arms 20 of the lift 15, comprising a part of the portion 17 of the counter base 15 left exposed between the said arms 20.

I prefer to have the rear portion 21 of the lift 14 of appreciable width, and to taper the arms 20 from the said rear portion 21 to the extreme front ends, where they may terminate in sharp corners, to meet the corresponding corners of the counter base 15. It will be thus noted that by making the lift 14 of yielding material, a heel structure is provided having a high degree of resiliency, and providing a peculiar cushion. It will be further noted that, notwithstanding the skeleton structure of the tread portion of the heel as described, there is provided a heel base of maximum dimensions, the outer lateral dimensions being full and complete, and the open structure being confined to the interior portion. It is understood that in some cases the rolled counter edges may be omitted and other changes may be made without departing from the spirit of my invention.

The rolled edge 11 of the sole portion is of the usual roughened or corrugated form, being an extension of the adjacent tread portion of the sole. The rolled heel edge 12 as mentioned is similarly an extension or a continuation of the counter bottom 15, which counter bottom and rolled edge are similarly roughened or corrugated, as shown, a portion of the said corrugated lower side of the bottom 15 being exposed at 17 between the arms 20 of the lift 14. As shown in the sectional view in Figs. 4 and 5 the lift 20 is united to the counter bottom 15 in such a manner as to form a unitary or essentially integral structure, no rivets or metallic connecting means being employed. By 110

the construction described a rolled heel edge 12 is provided above the lift 14 that has a roughened or corrugated outer surface.

The construction may be readily understood by noting that the heel portion of the counter bottom 15 is of greater area than the portion of the heel lift 14 opposed thereto, and is of sufficient area to extend along the lateral edges of the heel structure, suitably to provide a portion exposed along the said edges so as to form the rolled heel edge 12, and by noting also that another portion comprising a part of the body portion of the said counter bottom 15, designated as 15 17, is opposed between the arms 20 of the said heel lifts 14, which latter is U-shaped. The fact that the exposed surfaces of the said rolled heel edge 12 and the exposed body portion 17 are of rough or corrugated 20 character follows from the fact that the entire surface of the counter bottom 15 is corrugated including the portion exposed to and secured to the heel lift 14, so that any portion that may not be covered by the said heel lift 14 must present a rough or corrugated surface.

The difficulty heretofore has been to secure the heel 14 to a corrugated surface, such as described, but this I have succeeded 30 in overcoming by methods which I have de-

vised, and which I operate to produce a product such as shown and described.

Aside from the corrugated feature of the counter bottom 15 and the heel lift 14, it will be noted that the said counter bottom 15 serves simply as a closure for the bottom of the heel, and may be only of such thickness as is necessary to effect such closure, and which will accordingly be somewhat yielding, corresponding to such thickness, 40 and the heel lift 14, because of the U-shape of construction as shown and described, permits of such yielding, particularly so between the arms of the lift.

45

I claim as my invention:—

In rubber foot wear, a heel structure comprising a counter closed on the lower side by a counter base and a lift secured directly to the said counter base, the said lift being of U-shape, fitting around the edge portions only of the said counter base, and leaving a portion of the said counter base, between the arms of the said lift, uncovered, whereby the support for the said counter base provided by the said lift is confined to the said edge portions thereof.
